UNITED STATES PATENT OFFICE.

ARTHUR W. ROBINSON, OF MONTREAL, QUEBEC, CANADA.

DIPPER-DREDGE.

1,323,323.

Specification of Letters Patent.

Patented Dec. 2, 1919.

Application filed March 31, 1919. Serial No. 286,398.

To all whom it may concern:

Be it known that I, ARTHUR W. ROBINSON, a citizen of the Dominion of Canada, and a resident of the city of Montreal, Province of Quebec, Dominion of Canada, have invented certain new and useful Improvements in Dipper-Dredges, of which the following is a specification, reference being had to the accompanying drawings.

10 This invention pertains to that class of dredge in which a single dipper is employed mounted on the end of a rigid dipper arm, which is raised or lowered by suitable hoisting mechanism; and it relates more particu-
15 larly to the construction and arrangement of the means for hoisting the dipper and of feeding it in or out so as to alter the radius of the dipper arc, to the construction and arrangement of the sheaves for guiding the
20 hoisting and other ropes which effect the movements of the dipper, and finally to an improved arrangement of the backing line which draws the dipper rearwardly.

This invention is a further development
25 of and improvement upon that set forth in my United States Letters Patent No. 1,081,774 dated December 16, 1913, in which a somewhat similar arrangement of certain of the parts is shown; but in my present invention the arrangement of the sheaves, the manner of controlling the feeding of the dipper arm and the arrangement and manipulation of the backing line are all essentially different, from which differences flow
35 a series of advantages which will be referred to below.

Referring to the drawings, Figure 1 is a side elevation of the parts as assembled and mounted on the front end of a dredge
40 scow; Fig. 2 is a plan view of the boom, showing the construction and arrangement of the sheaves, ropes and dipper arm support; Fig. 3 is an end view of the lower sheaves located in the scow; Fig. 4 is a view
45 of the forward end of the scow corresponding to Fig. 1, but with the boom turned at right angles, thus showing the twist of the hoisting ropes; Fig. 5 is an elevation, somewhat enlarged, of the support for the dipper
50 arm upon the boom.

In the drawings 1 represents the scow, 2 the boom or swinging member, 3 the top stay by which the boom may be supported from the usual frame 4, which is supported by
55 back stay 5. 6 is the dipper arm, 7 the dipper, 8, 8, double hoisting ropes, which pass

from the dipper 7 over two sheaves 10, 10, spaced apart as shown and suitably supported at the forward end of the boom, thence over two sheaves 9, 9, suitably mounted near the lower end of the boom and separated by a distance sufficient to allow the dipper arm 6 to freely pass between the ropes 8, 8, thence under sheaves 11, also spaced apart as shown and suitably supported in the hull of the scow, thence off to the usual winding or hoisting drum, not shown. 12 is the usual turn table, 13, see Fig. 5, is a smooth roller supported upon a shaft 14, which is journaled upon the boom. 70 The roller acts as the support on the boom for the dipper arm and the movements of the dipper arm are effected and controlled by wire ropes which are received within a circumferential recess 15 in the center of 75 the roller 13, so that it also acts as a sheave for these ropes, one of which 16, passes over this roller and is attached at one end to the lower part of the dipper arm, as shown, while the other one, 17, passes under the 80 roller and is attached to the upper end of the dipper arm, as shown. The opposite ends of both ropes are attached to a drum 18 mounted on the lower part of the boom and which is actuated by a suitable motor 19, 85 pinion 20 and gear 21. The dipper arm is retained in place on the roller 13 by a saddle block 22, which incloses it and through which it freely slides when actuated and controlled by the ropes 16 and 17. The 90 drum 18 is provided with the usual friction brake, not shown, to control the too free downward movement of the dipper arm and through the instrumentality of the steam or other motor 19 and its associated gearing, 95 the dipper arm will be moved in or out by power. This is of special advantage in controlling the position of the dipper both while dredging and while getting into position for dumping. 23 is the backing line, so 100 called, necessary or useful in this type of dredge to pull the dipper to working position. It is connected as at 24 to the dipper arm, passes through a fair lead 25 at or near the base of the boom up over a grooved 105 sheave 26, around another grooved sheave 27 supported in the hull between the sheaves 11, see Fig. 3, and thence to the hoisting machinery in the usual way.

It will be noted that although I employ 110 in this invention here and there a known feature or element, yet that some of them are

entirely new and furthermore that when all the elements are constructed and assembled as described and illustrated, I secure a series of advantages never before realized, among 5 them the following:

I retain the advantage of two parallel hoisting ropes, which act as one, and are spread apart for the purpose of permitting a solid dipper arm to work between them, 10 instead of incurring the expense of a split dipper arm, or the defective operation of a dipper arm the hoist for which is on one side only. The feed of the dipper arm has in many instances heretofore been controlled 15 by rack and pinion with friction brake, which are liable to disorganization because of wear and breakage due to the great weight of the dipper arm and its load resting on the pinion and also because of the excessive 20 strains to which it is subjected in use. These objections are avoided by the employment under my invention of a smooth solid roller as the support for the dipper arm. The movement of the arm is controlled by wire 25 ropes located within and protected by a recess in the center of the roller. It thus acts as a reliable and durable support for the dipper arm, there being extended contacting surfaces between them, and also as a sheave 30 for the ropes. The wire ropes provide a powerful and flexible control and the drum and gear to which they are attached are situated on or near the base of the boom near the center of motion where their momentum, 35 due to swinging, is less, in fact, being to the rear of the center, they act more or less as a counterbalance for the boom, instead of injuriously loading it near the middle, as when rack and pinion attachments were 40 used; and, as stated, the employment of a motor to control and actuate the feed of the dipper arm greatly facilitates its operation. The spreading of the main hoisting ropes in the manner described not only provides for 45 a solid dipper arm between them, but enables me to employ a centrally located backing line, which is carried out to the dipper arm on the axis of rotation of the turn-table. The fairlead, through which it passes, 50 is always fair because it is attached to and moves with the base of the boom, thus avoiding the objectionable features in fairleads as heretofore used, due to the bend in the backing line occasioned by the degree to which 55 the boom is swung, which, on many occasions, was so sharp as to injure the line. In some instances also where the fairlead has been placed in the hull, if rough water was encountered, it has been admitted through 60 the fairlead opening, necessitating pumping, or other operation for its removal. In addition to this also, instead of having the sheaves 9, 9, on the boom inclined to each other, as in my former patent, I now make 65 them parallel and correspondingly spread

the lower sheaves 11, 11, thus not only providing for the backing line, but also making a better and simpler construction at reduced cost. It will be noted that the hoisting ropes between the sheaves 9 and 11 pass vertically 70 in substantially the axis of rotation of the turntable. Thus they twist on one another to a slight extent during the swinging of the boom and are not always in the plane of the sheaves; but it is found in practice that 75 a slight deviation is quite permissible and the very small angle is taken care of by the flanges forming the grooves of the several sheaves.

I wish it to be understood that the description and drawings hereof disclose one form only of dredge mechanism in which my invention may be embodied, because those familiar with such matters will at once understand that my improvements, wholly or 80 in part, may be embodied in mechanism quite widely different from that which I have described and illustrated. For instance, the dipper hoisting ropes are shown as a pair of single ropes separated by a space sufficient 85 to permit the dipper arm to operate between them, but, as is well known, each member of the pair may consist of more than one rope. This is desirable in heavy work because a number of small ropes, while equaling the strength of a single large one, will have greater flexibility and therefore require less power. The peripheries of the guide sheaves will, of course, be made to correspond to the special construction of 90 hoisting ropes. When in the claims I refer to duplex hoisting ropes, I mean that there shall be a pair separated as stated in the specification, irrespective of the number of individual ropes comprised in each member 95 of the pair. Also, although I prefer that the winding drum for the ropes 16 and 17, which control the dipper arm, and the motor therefor, if one be used, shall be at the base of the boom and in rear of the axis of 100 the turntable, since, as stated, certain important advantages result from that construction and arrangement, yet, if preferred, these parts may be located wherever they will efficiently perform their functions. It 105 will therefore be obvious to those who are familiar with such matters that modifications may be made in the details of construction of the parts described and illustrated without departing from the essentials of the 110 invention. I therefore do not limit myself to such details.

I claim:

1. In a dipper dredge, embodying among other things the usual A frame or mast, and 115 a swinging boom, a dipper arm supported thereby, a combined sheave and roller supported on the boom with which the dipper arm engages, a single winding drum, ropes attached respectively at one of their ends to 120

130

the upper and lower parts of the dipper arm and passing respectively under and over the combined sheave and roller and attached at their other ends to the winding drum in such 5 manner that its rotations will wind and unwind them respectively, and means to control the rotations of the drum.

2. In a dipper dredge embodying among other things the usual A frame or mast and 10 a swinging boom, a dipper arm supported thereby, a combined sheave and roller supported on the boom and supporting the dipper arm, a single winding drum, ropes attached respectively at one of their ends to 15 the upper and lower parts of the dipper arm and passing respectively under and over the combined sheave and roller and attached at their other ends to the winding drum in such manner that its rotation will wind and 20 unwind them respectively and means to control the rotations of the drum.

3. In a dipper dredge embodying among other things the usual A frame or mast and a swinging boom, a dipper arm supported 25 thereby, a combined sheave and roller supported on the boom with which the dipper arm engages, a single winding drum, ropes attached respectively at one of their ends to the upper and lower parts of the dipper 30 arm and passing respectively under and over the combined sheave and roller and attached at their other ends to the winding drum in such manner that its rotation will wind and unwind said ropes respectively, 35 and a motor adapted to positively rotate the drum in opposite directions.

4. In a dipper dredge, a swinging boom, a solid dipper arm supported thereby, a combined sheave and roller supported on the 40 boom with which the dipper arm engages, a winding drum supported upon the boom in rear of the axis of its rotation, ropes attached respectively at one of their ends to the upper and lower parts of the dipper arm 45 and passing respectively under and over the roller and attached at their other ends to the winding drum in such manner that its rotations will wind and unwind them respectively, and means to control the 50 rotations of the drum.

5. In a dipper dredge, a turn table, a swinging boom supported on the turn table, a solid dipper arm supported by the boom, a combined sheave and roller supported on 55 the boom, a winding drum and a motor supported upon the turn table in rear of its axis of rotation, ropes attached respectively at one of their ends to the upper and lower parts of the dipper arm and passing respectively under and over the combined sheave and roller and attached at their other ends to the winding drum in such manner as to be wound and unwound respectively by its 60 rotations, and means whereby the motor controls the rotations of the drum.

6. In a dipper dredge a swinging boom, a dipper arm supported by the boom, a combined sheave and roller supported on the boom and supporting and guiding the dipper arm and having a centrally located 70 circumferential recess and a smooth cylindrical surface at each side of the recess, a winding drum, ropes attached to the dipper arm and extending respectively under and over said combined sheave and roller within the recess therein and then to opposite sides of the winding drum so that its rotations will wind and unwind the ropes respectively, and means to control the rotations of the drum. 80

7. In a dipper dredge a swinging boom, a roller supported on the boom, a solid dipper arm supported by the combined sheave and roller, duplex hoisting ropes supported and guided by parallel sheaves arranged in pairs and separated by a distance at least equal to the width of the dipper arm, a winding drum, means on the dredge to guide said hoisting ropes to the winding drum, another winding 90 drum, ropes attached respectively at one of their ends to the upper and lower parts of the dipper arm and passing respectively under and over said combined sheave and roller and attached at their other ends to the last named winding drum, and means to control the rotation of the last named winding drum. 95

8. In a dipper dredge a swinging boom, a combined sheave and roller supported on the boom, a solid dipper arm supported by the roller, duplex hoisting ropes supported and guided by parallel sheaves arranged in pairs and separated by a distance at least equal to the width of the dipper arm, a winding drum, means on the dredge to guide said hoisting ropes to the winding drum, another winding drum, ropes attached respectively at one of their ends to the upper and lower parts of the dipper arm and passing respectively under and over said roller and attached at their other ends to the last named combined sheave and winding drum, and a motor adapted to positively rotate said last named drum. 110

9. In a dipper dredge a swinging boom, a combined sheave and roller supported on the boom, a solid dipper arm supported by the roller, duplex hoisting ropes supported and guided by parallel sheaves arranged in pairs and separated by a distance at least equal to the width of the dipper arm, a winding drum, means on the dredge to guide said hoisting ropes to the winding drum, another winding drum, ropes attached respectively at one of their ends to the upper and lower parts of the dipper arm and passing respectively under and over said combined sheave and roller and attached at their other ends to the last named winding 125 drum. 130

drum, and a motor adapted to positively rotate said last named drum, the said drum and the motor being in rear of the axis of rotation of the boom.

- 5 10. In a dipper dredge a turn table, a swinging boom supported on the turn table, a roller supported on the boom, a dipper arm supported by the roller, duplex hoisting ropes supported and guided by parallel
- 10 sheaves arranged in pairs and separated by a distance at least equal to the width of the dipper arm, a winding drum, means on the dredge to guide said hoisting ropes to the winding drum, another winding drum, ropes
- 15 attached respectively at one of their ends to the upper and lower parts of the dipper arm and passing respectively under and over said roller and attached at their other

ends to the last named winding drum, means to control the rotation of the last named 20 winding drum, and a backing line having a guide sheave on the scow the forward arc whereof is in the axial line of rotation of the turn table, another guide sheave on the boom the rearward arc whereof is substantially 25 in the axial line of rotation of the turn table and a fairlead on the turn table, the backing line being attached to the winding drum at one end, passing under and over the said guide sheaves respectively, 30 through the fairlead, and thence to the dipper arm.

In testimony whereof I have signed my name to this specification.

ARTHUR W. ROBINSON.
